Patented Sept. 20, 1921.

INVENTOR:

MRS. MARY ELINOR DELL,
Br: Otto H. Kueger,
her Atty.

UNITED STATES PATENT OFFICE.

MARY ELINOR DELL, OF GLENDALE, CALIFORNIA.

HYGIENIC GARTER AND SUPPORTER.

1,391,100.

Specification of Letters Patent. Patented Sept. 20, 1921.

Application filed January 25, 1921. Serial No. 439,727.

To all whom it may concern:

Be it known that I, Mrs. MARY ELINOR DELL, a citizen of the United States, residing at Glendale, in the county of Los Angeles and State of California, have invented a new and useful Hygienic Garter and Supporter, of which the following is a specification.

This invention relates to devices serving 10 the wearer for attaching and supporting various garments.

One of the objects of this invention is to provide a hygienic garment for women and children.

15 Another object is to have a garment swing from the shoulders so that the abdominal front is entirely free as used by adults.

Another object is to have the garment swing from the shoulders, the suspending 20 front members being provided with snap-buttons or fasteners and extra straps for fastening garments of children.

Another object is to provide a garment to or by which other pieces can be fastened 25 without unnecessary pressure to the wearer.

Other objects will appear from the following description and appended claim as well as from the accompanying drawing, in which—

30 Figure 1 is a perspective front view of the device, having a number of insertions illustrated, which are very desirable for athletic and swimming girls but normally are not absolutely necessary.

35 Fig. 2 is a front elevation of the upper portion of a sanitary napkin, to be attached to the front of the device.

Fig. 3 is a front elevation of the upper portion of a sanitary napkin, to be attached 40 to the rear of the device.

Fig. 4 is a fragmentary detail top edge view of a portion of the straps at a point where reinforced for holding buttons or fasteners.

45 Fig. 5 is a side edge view of the napkin, illustrated in Fig. 3.

Fig. 6 is a perspective front view of the device most suitable for everyday use.

Most garments and supporters to which 50 this device has relation and reference are worn and tied around the hip or waist or some other part of the body of the wearer, thereby naturally causing pressure, eventually on some vital organs.

55 This device is therefore principally suspended from the shoulders, and designed so

that other garments can be attached and supported.

In the illustration of Fig. 1, the shoulder straps 6 and 7 are provided with cross straps 60 8 and 9 in a position to come across the back over about the middle of the shoulder blades. A buckle or clasp 10 is provided for adjusting the space between the two shoulder straps 6 and 7. Other cross straps 11 and 65 12 are provided on the shoulder straps at about the point of the waist line of the wearer.

A buckle or clasp 13 is provided in these cross straps for adjustments between the shoulder straps at this point. The 70 straps 11 and 12 continue in the waist line or near this point and attach to the front portions of the shoulder straps, as indicated at 14. Garter tapes or straps 15 are secured to the lower terminations of the 75 shoulder straps by the buckles or clasps 16. Stocking grips 17 are provided near the lower terminations of the garter straps 15.

A number of buttons or snaps or fasteners 18 are provided for fastening other garments to this device and thereby supporting 80 such other garments by means of this garment or device. At all points where the cross straps pass over the shoulder straps, there is naturally a double thickness of material, sufficient to securely hold a fastener, but at the points 19 in the back straps 11 and 12 there is naturally only a single thickness of material. This is preferably reinforced by an extra piece of material as indicated in the illustration in Fig. 4, the 85 cross straps 11 being provided with the reinforcing piece 20 to securely hold the fastener 18.

The corresponding members of fasteners 21 are secured to the sanitary napkin 22, illustrated in Figs. 3 and 5 in a position to engage with the fasteners at the points 19 in the back straps. Other corresponding members or fasteners 23 are provided on the straps 24 of the sanitary napkin to engage with the fasteners on the front 90 portions of the shoulder straps at about the points 14. The garter part of the device is preferably of non-elastic web in the whole length. The shoulder straps are preferably 100 of non-elastic web, in Fig. 1, however, illustrated as provided with short insertions of elastic material at suitable and desired points as indicated at 26, 27, 28 and 29. The take-up and let-out plan for sizes, possible by 105 the use of the several clasps and buckles, is 110 preferably made in the front and back of

the shoulder straps at well chosen places; but, naturally, more of such adjusting means can easily be provided for athletic and swimming girl; and, for the very exacting girl, 5 the entire supporter can even be made of very strong elastic web. The whole device can naturally also be made of very fancy web, silk if need be, and of colored cotton web. By the use of elastic insertions 30 and 10 31 in the back straps across the back, a very fine shoulder brace is provided. This brace is for correcting the tendency to round shoulders and tends to prevent a developing of round shoulders. The extension ends, 15 illustrated and indicated in dotted lines at 33 and 32, are attachments to be used for children to continue the straps from the points 14 in the front portions of the shoulder straps. Extra fasteners 34 are provided 20 on these extensions for fastening children's garments.

In the illustration in Fig. 6, the shoulder straps 35 and 36 are naturally the equivalents of the shoulder straps 6 and 7 illustrated in Fig. 1. This illustration, in Fig. 6, represents the device most practical for the everyday use. The lower ends 37 may, of course, be of any suitable length for adjustably holding stocking grips. The material of the device is preferably of strong non-elastic web. The web, being non-elastic, does away with the usual unsatisfactory perishable elastic web. The garment may be washed and not injured. The life of 30 the garment is therefore measured and subject only to the durability of the web used. The same garter attachments, indicated at 35 15, 16 and 17 in Fig. 1, may naturally also be used on the lower ends 37 of the shoulder 40 straps 35 and 36. There may also, naturally be any number of buttons or fasteners for attaching petticoats, dress skirts, shirt-waists, and other similar garments so used and attached. The back strap 38 is the 45 equivalent of the back straps 8 and 9, and serves the same purposes, namely to help to prevent round shoulders. Other straps 39 are preferably arranged to reach around the whole body so as to keep the device or

garment in place, comfortably supporting 50 and confining the bust and at the same time loosely encircling the body, having on the front ends 40 of these straps a suitable number of fasteners 41. The lowermost strap 42 is preferably arranged to only reach over 55 the back and the sides, leaving a clear and free space between the points 43. The whole garment swings freely from the shoulders, thereby making it a comfortable and satisfactory supporter and device of its particular class. It leaves the abdominal front free. The whole device can easily be arranged as described above in relation and with reference to Figs. 1, 2, and 3; and can easily be provided with any suitable 60 number of insertions and attachments for the athletic and swimming girl, as will easily be understood, without departing from the principle of this invention.

Having thus described my invention, I 70 claim:

In a garment, shoulder straps to come over both shoulders of the wearer having means to receive garters on all four terminations, the shoulder straps being of non-elastic material, insertions of elastic material, of proportionally short sizes, in both shoulder straps at points in front and the back of the wearer, adjusting means in the elastic portions, cross straps between the 75 shoulder straps extending around the body of the wearer up to the space between the front portions of the shoulder straps, the cross straps being mainly of non-elastic material, insertions of elastic material of proportionally short sizes, in the back portions 80 of the cross straps, adjusting means in the elastic insertions in the cross straps, and means for attaching other garments to the 85 device.

In testimony that I claim the foregoing as my invention I have signed my name in the presence of two subscribing witnesses.

MRS. MARY ELINOR DELL.

Witnesses:

CECIL E. MAY,
CHARLOTTE STEPHENS.
